CLAIM

The ornamental design for a disaster flotation device, as shown and described.

DESCRIPTION

FIG. 1 is a top view of a disaster flotation device showing my new design;

FIG. 2 is bottom view of the disaster flotation device thereof; FIG. 3 is a left-side view of the disaster flotation device thereof;

FIG. 4 is a right-side view of the disaster flotation device thereof;

FIG. 5 is a front view of the disaster flotation device thereof; FIG. 6 is a rear view of the disaster flotation device thereof;

FIG. 7 is a top perspective view of the disaster flotation device thereof; and,

FIG. 8 is a bottom perspective view of the disaster flotation device thereof.

1 Claim, 8 Drawing Sheets
